POCKET WEARING APPAREL BRUSH

Samuel M. Abrams and Albert Abrams, New York,
N. Y., assignors to Knomark Manufacturing
Co. Inc., Brooklyn, N. Y., a corporation of New
York

Application October 1, 1949, Serial No. 119,086

1 Claim. (Cl. 15—184)

1 This invention relates to hand brushes, and more particularly is directed to portable hand brushes of compact construction each provided with a handle carrying case from which a bristle member of the brush can be adjustably projected from a fully concealed position to an effective position for use. Such hand brushes are adapted to be conveniently carried about the person or in handbags and readily set-up for clean sweeping wearing apparel. Examples of such brushes are metallic bristle pocket brushes for use in restoring attractive finishes of suede shoes, and for other personal purposes.

Among the objects of the invention is to generally improve hand brushes of the character described comprising few and simple parts, which shall be easily and readily assembled to provide compact yet attractive appearing personally carried articles of recognizable utility, which shall be relatively cheap to manufacture, which shall provide ready means to adjustably project bristle members from fully concealed positions within handle carrying cases to effective positions for use, and which shall be practical and efficient to a high degree.

Other objects of this invention will in part be obvious and in part hereinafter pointed out.

The invention accordingly consists in the features of construction, combination of elements and arrangement of parts hereinafter described, and of which the scope of application will be indicated in the claims following.

In the accompanying drawing in which possible illustrative embodiments of the invention are shown.

Fig. 1 is a front elevational view showing a pocket or handbag wearing apparel brush in a fully open position with the bristle member extended from its handle-holder in an effective position ready for use and constructed to embody the invention.

Figs. 2 and 3 are side elevational and bottom plan views, respectively, of the improved brush as shown in Fig. 1.

Figs. 4 and 5 are enlarged cross sectional views taken on line 4—4 in Fig. 1 and line 5—5 in Fig. 4, respectively, showing the interior construction of the improved brush.

Fig. 6 is an exploded side elevational view of the bristle member and finger knob removed from the handle-holder, and

Fig. 7 is a front elevational view similar to Fig. 1 but showing the improved brush in compact closed position with the bristle member retracted and fully concealed in the handle-hold-

er, and showing the bristle member in dotted lines in a partly open position, that is, partially extended to an effective position for use in so-called "stubborn" requirements.

Referring in detail to the drawing, 10 denotes a hand brush constructed to embody the invention provided with a handle-casing or holder 11 into which a bristle carrying member 12 telescopes, that is, can be slidingly projected from a fully concealed position, shown in Fig. 7, to effective positions for use, shown in Figs. 1 and 2, and in dotted lines in Fig. 7.

Handle-casing 11, as is clear from Figs. 3, 4, and 5, may be a shell or container-like enveloping closure structure having an open end 11a through which bristle member 12 moves from said concealed position shown in Fig. 7 to the effective using positions, shown in Figs. 1 and 2, and in dotted lines in Fig. 7. Said handle-casing 11 may be made of metal or other suitable sheet material and preferably is molded of a thermoplastic resin with an integrally formed rim ledge 11b about said open end 11a and having a continuous structure reinforcing rib or fin 11c centrally extending about the length and width of said casing 11 between spaced apart ends of the rim ledge 11b, said rib 11c being integrally formed as part of the casing 11 together with rim ledge 11b.

Hand-brush 10 may be constructed to accommodate a bristle carrying member 12 of various cross-sectional shapes, such as, round, oval and square or modifications thereof. For personal use in restoring the appearance of wearing apparel said bristle member 12 may be made with a plurality of rows of tufts 12a of hair or plastic bristles carried by a backing piece 12b and for use on suede shoes it has been found that such tufts 12a may be of a suitable metallic bristle, such as brass or bronze. As shown in the drawing, bristle carrying member 12 having said rows of tufts 12a requires a correspondingly shaped handle-casing 11 with a flattened front wall 11d parallelly aligned with a rear wall 11e. Front wall 11d may have a central passage or slot 11f through which a rider 14 knob headed at 14a freely extends carried by backing piece 12b of bristle carrying member 12.

It is desirable that the bristle carrying member 12 be releasably retained and fully shielded in extreme retracted compact position concealed within handle-casing 11 when not in use as shown in full lines in Fig. 7, and that handle-casing 11 releasably retain said member 12 when fully extended, as shown in Figs. 1 and 2, so that

the handle-casing 11 serves as efficient finger gripping means for the bristle carrying member 12 for a brushing operation which permits flexing the entire lengths of the bristle tufts 12a. Also bristle tufts 12a should be selectively retained in an intermediate projected position as is clear from the dotted line position shown in Fig. 7, so that the effective flexing length of bristle tufts 12a is shortened for relatively stiffer brushing by brush 10 as required in so-called "stubborn" cleaning operations that is, for removing excess soil or deeply penetrated stains.

For "stubborn" cleaning operations, suitable means may be provided, for example, as shown in the drawing, edge portions of flattened front wall 11d bordering slot 11f are formed with spaced apart notches, 11g, 11h and 11j for selectively engaging with resilient longitudinally partially split shank 14b of rider 14 with shank split 14c extending through knob 14a and springingly spread. Said rider 14 may be made of any suitable spring forming material, either metal or plastic, having end 14d opposite knob 14a firmly anchored in the backing piece 12b, said slot 11f being of a width to permit sliding movement of the rider shank 14b when the split knob 14a has finger pressure applied to bring the spread of the shank split to a minimum.

Notches 11g when releasably engaged by rider shank 14b seated therein retains the bristle carrying member 12 in said extreme retracted position, notches 11h so retain member 12 in said fully extended position, and notches 11j in said intermediate position, above described.

From the above description and the drawing the utility of the invention is readily understood. The improved brush 10 after being assembled as shown in Figs. 1 to 5 has backing piece 12b of bristle carrying member 12 interlocked by rider 14 for limited sliding movement in and out of said open end 11a of handle-casing 11. The tufts 12a are permanently set, that is, anchored into backing piece 12b as shown at 12c in Fig. 4.

Bristle carrying member 12, in fully extended position shown in Figs. 1 to 5, permits handle-casing 11 to be conveniently grasped by the fingers of the user and the effects of the full length of tufts 12a swept over the surface to be cleaned in the well understood manner. Rider 14 has the split shank 14b thereof sprung into notches 11h to effectively prevent the bristle carrying member 12 from accidentally backing up into the handle-casing 11.

Where stiff brushing is required, the knob 14a is finger pressed to close the slit 14c, thereby releasing the split shank 14b from engaging with notches 11h, and rider 14 is slid along slot 11f with bristle carrier member 12 until the split shank 14b registers in alignment with notches 11j. On releasing knob 14a, shank 14b will spring apart to engage in said notches 11j and will position the lengths of tufts 12a partially beyond handle-casing 11 as shown in dotted lines in Fig. 7 thereby exposing a shorter than full length of said tufts 12a to present an effectively stiffer abrasive brushing means for use in "stubborn" requirements.

When brushing operations have been finished, hand brush 10 may be collapsed into a compact body by finger pressing knob 14 as above described to release the split shank 14b from en-

gagement with either notches 11h or 11j and then sliding rider 14 in slot 11f until the split shank 14b registers in alignment with notches 11g. On releasing said finger pressure from knob 14a, shank 14b will spring apart at split 14c to engage in said aligning notches 11g and will be effective to positively retain the tufts 12a concealed wholly within handle-casing 11, as is clear from the full lines of Fig. 7. In this collapsed compact form, hand-brush 10 may be conveniently carried in the pocket or handbag and the tufts 12a shielded by the handle-casing 11 against soiling linings or other contents in such pocket or handbag.

It is therefore seen that there is provided improved hand brush in which the objects of the invention are achieved and which are well adapted to meet all conditions of practical use.

As various possible embodiments may be made in the above invention for use for different purposes and as various changes might be made in the embodiments above set forth, it is understood that all the above matters here set forth, or shown in the accompanying drawing are to be interpreted as illustrative and not in a limiting sense.

Thus having described my invention, we claim as new and desire to secure by Letters Patent:

A pocket wearing-apparel brush comprising a handle-casing formed with a flat wall and an open end, a bristle carrying member mounted for sliding movement into and out of said handle-casing through said open end, said handle-casing having a depth greater than the length of said member and bristles in the direction of said sliding movement so that said member and bristles are completely housed and concealed in said casing when in a fully retracted position and in an effective brushing position when said bristles are extended beyond said handle-casing open end, said casing flat wall formed with an elongated slot extending therethrough in the direction of said sliding movement, a finger actuated rider carried by said member to extend through said slot to produce said sliding movement upon the application of pressure, a strengthening ledge integrally formed as a rim extension about said casing open end, and a portion of said rider extending through said slot having a split resilient shank end formed to terminate beyond said casing, edge portions of said casing flat wall bordering said slot being formed with notches for engagement by said split shank end for releasably retaining said member with the bristles in predetermined effective positions beyond the casing.
